(57) **CLAIM**

The ornamental design for a video stabilizer for smart phone or tablet, as shown and described.

DESCRIPTION

FIG. 1 is a first perspective view of a video stabilizer for smart phone or tablet showing our new design;
FIG. 2 is a second perspective view thereof;
FIG. 3 is a third perspective view thereof;
FIG. 4 is a fourth perspective view thereof;
FIG. 5 is a front elevational view thereof;
FIG. 6 is a rear elevational view thereof;
FIG. 7 is a right side view thereof;
FIG. 8 is a left side view thereof; and,
FIG. 9 is a top plan view thereof.

The broken lines are for illustrative purposes only and form no part of the claimed design.
